UNITED STATES PATENT OFFICE.

JULIAN O. ELLINGER, OF NEW YORK, N. Y.

REINFORCEMENT FOR CONCRETE CONSTRUCTION.

No. 890,033.

Specification of Letters Patent. Patented June 9, 1908.

Application filed March 4, 1907. Serial No. 360,310.

To all whom it may concern:

Be it known that I, JULIAN O. ELLINGER, a citizen of the United States, and residing in the city, county, and State of New York, have invented certain new and useful Improvements in Reinforcements for Concrete Construction, of which the following is a specification.

This invention relates to improvements in reinforcements for beams, girders and the like, having their body portions composed of concrete or analogous plastic materials.

It particularly relates to reinforcements wherein all of the elements of the reinforcement are designed, built, delivered, and erected with all parts securely held together so that none will be inadvertently omitted when the concrete is molded around the same, and comprises longitudinally extending tension members connected with each other by loops or stirrups adapted to take care of the shearing stresses.

One of the objects of the invention is to provide a reinforcement of the character stated, which will be very efficient in use and may be inexpensively produced. In pursuance of this object I have produced a beam or girder having longitudinally extending rods or bars, forming tension members, and a shear member composed of a fixedly united system of longitudinal and transverse rods which are arched between the tension members and are suitably secured to the latter. Such a construction forms a beam or girder which may be produced at a minimum expense, and one in which strain imposed on any part of the shear member is transmitted throughout the series of longitudinal and transverse bars composing the same, and also to the tension members, thus making the entire network available to support strain imposed on any part thereof and to transmit the same to the tension members. This feature, however, is not broadly claimed herein as it is made the subject matter of claims embodied in my copending application No. 373,633, filed May 14, 1907.

In further pursuance of the ultimate object of the invention, the tension members, which are located at opposite sides of the beam or girder, are each formed of two rods or bars connected with each other by a web from which the ends of one of the rods or bars of each pair are severed and bent upward. Among the advantages which this construction affords, especial attention is called to

the fact that the web and rods of the shear members lend themselves to an effective and yet economical mode of connecting the shear member to the tension members and to the 60 positioning of the beam or girder in the mold, which, as herein shown, may be produced merely by extending the ends of the transverse rods of the shear member through apertures in the webs, and bending some of said 65 ends into contact with the outer faces of the web, allowing others of said ends to extend directly outward sufficiently to engage the side walls of the form and bending still others downward and extending them sufficiently 70 to engage the bottom of the form.

Other objects will appear from the herein-after description.

The objects are accomplished by the construction set forth in the following description 75 and illustrated in the accompanying drawing.

Referring to the drawing, Figure 1 is a perspective view of a reinforcement made in accordance with the present invention and shows the preferred construction thereof. 80 Fig. 2 is a detail plan view of the means which constitute the shear member of the reinforcement. Fig. 3 is a sectional view of the reinforcement and the form in which the same is placed preparatory to the molding of the 85 concrete or other plastic material around the reinforcement.

The same reference character designates the same part in the several views.

The present reinforcement comprises a pair 90 of side members A and A' each of which consists of a pair of rods a, a' connected with each other by a web a² of thin sheet metal and adapted to be rolled, pressed or otherwise produced of the required shape. The rod a' of each of these side members is sheared from the web a² at each end a suitable distance toward the center, and is left unsevered at the central portion. The ends of the rods a' thus severed from the web are then 100 bent upward at an inclination to form the divergently inclined portions 1.

At suitable distances apart apertures 2 are provided in the webs of the members A', A² for the reception of the ends of stirrups or 105 loops b which are preferably of inverted approximately V form. The ends b' of some of these rods b are turned downward to rest on the bottom d of the form D and thereby support the reinforcement within said form during the process of forming the concrete or 110 other material around the reinforcement.

The ends b'' of others of the loops or stirrups extend outward from the webs to the sides d' of said form and thus center the reinforcement in the latter; while the ends b''' of still others of the loops or stirrups may be bent into close engagement with said webs and thus serve to prevent separation of the two side members of the reinforcement.

Along the top of the loop or stirrups extends a longitudinal rod c which connects the several loops or stirrups with each other and braces and properly spaces the same, and may, if desired, be fixedly secured thereto in any suitable manner. Similar longitudinal rods c' near the ends of the loops connect the loops or stirrups with each other and space the same.

As shown in Fig. 2, the shear member B is formed from a net work of longitudinal rods c, c' and transverse rods 6, connected with each other, and are adapted to be bent to form a connected series of loops or stirrups of approximately inverted V shape with projecting ends by which the shear member may be fixedly secured to the side members A and A' of the reinforcement, and centered vertically and laterally in the form.

The loops or stirrups may be arranged at any suitable distance apart and they may be parallel with each other, or extend at any desired angle with relation to each other. While I have shown the loops or stirrups placed the same distance apart, yet it is preferred to place them closer together near the ends of the reinforcement than at the center, as the shearing stresses are greatest at the ends of the beams or girders. These loops or stirrups may be arranged vertically or inclined. Those at one side of the longitudinal center of the reinforcement are preferably inclined in a direction the reverse of those at the other side thereof. This inclination and relative arrangement of the loops or stirrups may be readily produced when made of the material shown by Fig. 2 of the drawing, by cutting the longitudinal rod c between two of the rods b at or near the center of the reinforcement, and then forcing all the rods at one side of the longitudinal center towards one end of the reinforcement and all the rods on the other side of said center towards the other end of the reinforcement.

It will be understood that in the use of the reinforcement described, the rods or bars a form the principal tension members, the inclined portions l of the rods or bars a' resist the combined tensile and shearing stresses, which produce diagonal cracks in the concrete and the loops or stirrups resist the shearing stresses and transmit strains to the tension members.

From the foregoing construction the advantages of my invention will be readily understood, and while I have shown only one form thereof, it is to be understood that this

form is merely preferred and that many changes may be made therein and many apparently widely different embodiments of the invention may be made without departing from the spirit of the invention, for which reason the form herein described or shown in the accompanying drawings shall be interpreted as illustrative and not in a limiting sense. I desire it also to be understood that the language used in the following claims is intended to cover all of the generic and specific features of the invention and all statements or matters relating to or bearing upon the scope of the invention which, as a matter of language, might be said to fall therebetween.

Having described my invention what I believe to be new and desire to secure by Letters Patent is:

1. A reinforcement for concrete and other material having at each side thereof a tension member composed of a plurality of rods or bars and an apertured web connecting the same with each other, between their ends and extending along one of said bars, and separately formed arms arranged between said side members and arched between the same, having their ends projecting through the apertures in the webs thereof.

2. A reinforcement for concrete and other material having at each side thereof a tension member composed of a plurality of rods or bars and an apertured web connecting the same with each other, between their ends and extending along one of said bars and separately formed arms arranged between said side members and arched between the same, having their ends projecting through the apertures in the webs thereof and bent to position the reinforcement in the form.

3. A reinforcement for concrete and other material, having side members each composed of a plurality of rods or bars in different planes, and an apertured web connecting the same with each other, between their ends and extending along the lower bar, and separately formed arms arranged in arched loops between said side members and having their ends projecting through the apertures in the webs thereof.

4. A reinforcement for concrete and other material, having side members each composed of a plurality of rods or bars in different planes, and an apertured web connecting the same with each other, between their ends and extending along the lower bar and separately formed arms arranged in arched loops between said side members and having their ends projecting through the apertures in the webs thereof and bent to position the reinforcement in the form.

5. A reinforcement for concrete and other material, having side members each composed of a plurality of rods or bars in different planes, and an apertured web connecting

the same with each other, between their ends and extending along the lower bar, and separately formed arms arranged in arched loops between said side members and having their 5 ends projecting through the apertures in the webs thereof and variously bent to position the side members with respect to each other and in the form.

6. A reinforcement for concrete and other 10 material having at each side thereof a tension member composed of a plurality of rods or bars and an apertured web connecting the same with each other, and a network of fixedly united longitudinal and transverse 15 rods or arms, said network being arched between said tension members and having ends of its transverse rods or arms extending through the webs.

7. A reinforcement for concrete and other 20 material having at each side thereof a tension member composed of a plurality of rods or bars and an apertured web connecting the same with each other, and a network of fixedly united longitudinal and transverse 25 rods or arms, said network being arched between said tension members and having ends of its transverse rods or arms extending through the webs and variously bent to position the reinforcement in the form.

8. A reinforcement for concrete and other 30 material having at each side thereof a tension member composed of a plurality of rods or bars and an apertured web connecting the same with each other, and a network of fixedly united longitudinal and transverse 35 rods or arms, said network being arched between said tension members and having ends of the transverse rods or arms extending through the webs, some of said ends being 40 bent to engage the faces of the webs, others bent downward to engage a wall of the form and others extending outward approximately straight to engage another wall or walls of the form.

9. A reinforcement for concrete and other 45 material, having at each side thereof a tension member composed of a plurality of rods or bars and an apertured web connecting the same with each other, separately formed 50 transversely-extending bent rods or arms having ends extending through the apertures

in the web and a longitudinally extending rod or arm connecting the transverse arms with each other and fixedly united thereto.

10. A reinforcement for concrete and other 55 material, having at each side thereof a tension member composed of a plurality of rods or bars and an apertured web connecting the same with each other, separately formed transversely-extending bent rods or arms 60 having ends extending through the apertures in the web, and longitudinally extending rods or arms respectively arranged near the centers and ends of the transverse arms and connecting the same with each other and 65 fixedly united thereto.

11. A reinforcement for concrete and other 70 material, having at each side thereof a tension member, and a series of transversely extending oppositely inclined shear members at 75 each side of the longitudinal center of the reinforcement, each series comprising a plurality of downwardly open loops or straps arranged between said side member and to have flatwise engagement with the concrete, 80 and separate longitudinally extending arms each connecting the loops of each series together and fixedly united thereto, said shear members suitably secured to the tension members.

12. A reinforcement for concrete and other 85 material, having at each side thereof a tension member composed of a plurality of rods or bars and an apertured web connecting the same with each other, and a series of oppositely inclined shear members at each side of the longitudinal center of the reinforcement, 90 each series comprising a plurality of downwardly open loops or straps arranged between said side members and having their ends extending through the apertures in the webs, and longitudinally extending arms connecting the loops of the respective series together and fixedly secured thereto.

In witness whereof I have hereunto set my 95 hand at the city, county and State of New York, this 21st day of February, 1907.

JULIAN O. ELLINGER.
